UNITED STATES PATENT OFFICE.

PAUL R. JOHNSON AND FRED W. LODDING, OF WORCESTER, MASSACHUSETTS,
ASSIGNORS TO THE AMERICAN STEEL AND WIRE COMPANY OF NEW JER-
SEY, OF HOHOKEN, NEW JERSEY, A CORPORATION OF NEW JERSEY.

ADJUSTING MECHANISM FOR COLD-ROLLING MILLS.

1,108,447.

Specification of Letters Patent. Patented Aug. 25, 1914.

Application filed September 26, 1912. Serial No. 722,488.

To all whom it may concern:

Be it known that we, PAUL R. JOHNSON, a citizen of the United States, and FRED W. LODDING, a subject of the King of Norway, both residing at Worcester, in the county of Worcester and State of Massachusetts, have invented a new and useful Adjusting Mechanism for Cold-Rolling Mills, of which the following is a specification.

Our invention relates to the construction and arrangement of the means employed in manipulating the housing screws of rolling mills, and more particularly relates to the construction and arrangement of the adjusting mechanism used for adjusting the housing screws of cold rolling mills.

One of the most important features in the operation of a cold rolling mill is in securing and maintaining the fine adjustment of the rolls necessary to keep the top and bottom rolls in exact parallelism so that the rolled product will be of exactly uniform thickness. In the operation of cold rolling mills it is sometimes necessary to use one end more than the opposite end of the roll bodies which causes the pressure on the roll necks on one end of the rolls to be greater than that on the necks on the opposite end of the rolls. In such cases the roll bearings having the greatest pressure will wear much more rapidly than the others, which makes it necessary to adjust the housing screws in the opposite roll housings of the mill independently so as to maintain the rolls in axial alinement.

With the adjusting apparatus heretofore used in manipulating the adjusting screws in the top of the rolling mill housings a pinion which meshes with each of two gears on the adjustable housing screws is arranged so as to be disconnected from the pinions on the adjusting screws to make each housing screw independently operable. Each housing screw is then moved by means of a hand wrench independently adjusting the screws. After the necessary adjustment has been made, the pinion is then again caused to mesh with the gears on the adjusting screws so that when the pinion is moved the screws will be turned or rotated in unison.

One object of our invention is to provide a screw adjusting mechanism having novel means whereby the housing screws in the

top of the roll housing are connected and disconnected, and are adjusted conjointly and independently, as found necessary or desirable.

Another object of our invention is to provide a screw adjusting mechanism having novel means whereby the housing screws are manipulated in the successive adjustments of the rolls in the roll housings necessary in the operation of a rolling mill.

Further objects of the invention will appear hereinafter as the invention is more fully described and claimed.

Referring to the accompanying drawings forming part of this specification, Figure 1 is a plan showing a cold rolling mill having a housing screw adjusting mechanism thereon as constructed and arranged in accordance with this invention. Fig. 2 is an end elevation of the mill shown in Fig. 1. Fig. 3 is a side elevation of the apparatus shown in Figs. 1 and 2. Fig. 4 is a sectional elevation on a larger scale showing a detail of the adjusting mechanism forming part of this invention.

In the drawings, the numerals 2 and 3 designate the housings of a cold rolling mill having rolls 4 and 5 mounted therein. The windows 6 of the housings have top bearings 7 for the necks of the upper roll 4 and bottom bearings 8 engaging with the necks of the lower roll 5 mounted therein so as to be vertically adjustable. The rolls 4 and 5 are connected by coupling boxes 9 and spindles 10, of the usual construction, to the roll pinions (not shown).

The construction of the rolls, the bearings, and the roll driving mechanism being old and well known, and not forming part of this invention, is not further described.

The housings 2 and 3 are provided with housing screws 11 and 12 by which the top roll is adjusted and is held in position with respect to the bottom roll, the lower end of the housing screws 11 and 12 engaging with the top surface of the bearings 7 for this purpose.

The housing screw, which projects through internally threaded openings in the top of the housing 2, is provided on its upper end with a head in the form of a disk 13 having a hub 14 which is keyed or otherwise fastened to the housing screw so as to rotate therewith, and secured by one end so as to

extend vertically upward above the upper face of the head 13 is a series of cylindrical pins 15.

A spur gear 16 having an axial opening 17 and a series of openings or holes 18 in the web thereof is mounted on the upper end of the housing screw 11, the holes 18 being positioned in the gear 16 so that the pins 15 fixed by one end in the head 13 will extend therethrough and rotatably connect the head and gear. Also mounted on the upper end of the housing screw 11 above the top of the housing 2, so as to be lengthwise and angularly movable on the screw, is a sleeve or casing 19 which is provided with an annular flange, the upper edge 19^a of which is arranged to engage with the lower face of the gear 16 on the upper end of the housing screw 11.

20 Loosely mounted on the plain cylindrical upper end of the housing screw 11 below the casing 19, so as to be rotatable on the screw is a hand wheel 20 having a hub 21, the upper edge of which contacts with and supports the casing or sleeve 19. The lowermost edge of the hub 21 of the hand wheel has a helical face 21^a which engages with the anti-friction roller 22 on the end of the cap screw 23 which is secured to and extends 25 radially outward from one side of the housing screw 11. (See Fig. 4.) The housing screw 12 is also provided with a disk 13 having vertically extending pins 15, gear 16, sleeve or casing 19 and hand wheel 20, 30 constructed and arranged as has been described in connection with the housing screw 11.

The spur gears 16 on the housing screws 11 and 12 each mesh with a spur pinion 40 24 rotatably mounted on a bracket 25 which is secured in place on top of the roll housings 2 and 3. This pinion 24 has a face which is wider than that of the gears 16, 16, on the housing screws 11 and 12 to maintain the gears in mesh with the pinion 24 during the simultaneous vertical adjustment of the housing screws 11 and 12 necessary in the successive rolling operations.

45 The spur pinion 24 on the bracket 25 which is secured on the top of the housings 2 and 3 is keyed or otherwise secured to the shaft 26 for the operating spur gear 27, and mounted in bracket bearings 28, 29, secured on one side of one roll housing 2 is a vertical shaft 30 having a spur pinion 31 on the upper end thereof which meshes with the operating gear 27. The lower end of the shaft 30 is provided with any form of wrench 32 by which the adjusting screws 11 and 12 are manipulated in the roll adjusting operations.

In the operation of cold rolling mills provided with our improved adjusting mechanism the parts are assembled as is shown 60 and has been described. The housing screws

11 and 12 having been independently adjusted so that the faces of the rolls 4 and 5 are in exact axial alinement and the right distance apart, the metal being rolled is passed therebetween. Successive adjustments of the housing screws 11 and 12 are then made by manually swinging the wrench 32 which movements, through the pinion 31 and gear 27 turn the wide faced pinion 24 which is in mesh with the gears 16, 16, and 75 16 simultaneously turn the gears 16 and housing screws 11 and 12 to which they are secured. In the event of its becoming necessary to adjust one housing screw 11 or 12 in order to compensate for unequal wear of 80 the roll bearing or for other reason, the necessary one of the hand wheels 20 is turned manually. Such movement causes the helical face 21^a on the hub 21 of the hand wheel, by engagement with the anti-friction roller 85 22 on the radially extending cap screw 23, to temporarily lift the casing 19 and the housing screw gear 16 supported thereon, the gear moving vertically with respect to the pins 15 and the head 13 which are fixed 90 on the housing screws. The vertical movement of the housing screw gear 16 moves such gear out of engagement with the pinion 24 on the stand 25, the pins 15 being made of such length that the gears 16 can 95 be lifted vertically so as to be disengaged from the pinion 24 while still in engagement with the upper ends of the pins 15 on the head 13. The wrench 32 is then operated 100 manually to move the other housing screw 100 which is still operatively connected with the wrench so as to make the necessary amount of adjustment. While any form of hand wrench may be employed, a double-acting ratchet wrench is the preferred form. The 105 hand wheel 20 is then rotated in the reverse direction which movement lowers the housing screw gear 16 which it supports so as to again be in mesh with the pinion 24. The mill is then again operated as has been 110 described, the wrench 32 being employed to adjust the top roll 4 with respect to the bottom roll 5 in the successive passes of the material being cold rolled, and the hereinbefore described operations are repeated as 115 is found necessary from time to time.

The advantages of our invention will be apparent to those skilled in the art. By means of our improved construction the manually operated wrench is positioned conveniently for its ready manipulation. The provision of the separate gear detaching hand wheels enables the independent or simultaneous adjustment of each housing screw to be easily and quickly made. The 120 apparatus is simple and is easily kept in repair, and our improved mechanism can be readily applied to existing mills.

Modifications in the construction and arrangement of the apparatus may be made 130

without departing from our invention as defined in the appended claims.

We claim:

1. In a rolling mill, a roll adjusting mechanism comprising in combination housing screws for holding the rolls in adjusted position, gear wheels on said screws to rotate therewith, a pinion meshing with said wheels to turn the screws in unison, means for operating said pinion to adjust the housing screws, and means non-rotatably connecting the gear wheels and housing screws and permitting relative axial movement thereof in disengaging said gear wheels from the pinion.

2. In a rolling mill, a roll adjusting mechanism comprising in combination housing screws, screw adjusting gear wheels on said screws, a pinion meshing therewith to turn the wheels in unison, and means on each screw for detaching the gear wheel thereon from said pinion and permit independent adjustment of the housing screws.

3. In a rolling mill, a roll adjusting mechanism comprising in combination vertically extending housing screws, screw adjusting gear wheels on said screws, a pinion meshing therewith to turn the gear wheels in unison, a hand wheel on the screws to lift the gear wheels vertically thereon, and means operatively connecting the hand wheels and gear wheels.

4. In a rolling mill, a roll-adjusting mechanism comprising in combination housing screws for holding the rolls in adjusted positions, gear wheels on said screws to rotate therewith, a pinion meshing with said wheels to turn the screws in unison, means for operating said pinion to adjust the housing screws, and means non-rotatably connecting one of the housing screws and its gear wheel and permitting relative axial movement of said screw and gear wheel in disengaging said gear wheel from the pinion.

5. In a rolling mill, an adjusting mechanism comprising a pair of housing screws, cylindrical disks operatively connected with and arranged to rotate the screws, a gear wheel mounted on each of the screws above the disks, a pinion meshing with said wheels to turn the wheels, means connecting each disk and its gear wheel arranged to rotate said disk and gear wheel in unison, said means being arranged to permit relative axial movement of said gear and disk, and means rotatably mounted on each housing screw for moving the adjacent gear vertically relative to its disk to disengage the gear from the pinion.

6. In a rolling mill, a roll-adjusting mech-

anism comprising in combination a pair of housing screws for holding the rolls in adjusted positions, gear wheels on said screws to rotate therewith, a pinion meshing with said gear wheels to turn the screws in unison, a head fixed upon one of the housing screws to rotate therewith, means connecting the head and the adjacent gear wheel to rotate the head and gear in unison, said means being arranged to permit relative axial movement of the gear and the head, and means rotatably mounted on said housing screw for moving the gear vertically with respect to the head to disengage the gear from the pinion.

7. In an adjusting mechanism for rolling mills, the combination with a driving pinion, of a housing screw provided with a head fixed thereon to rotate therewith, a driven gear connected with the head to rotate therewith and capable of movement longitudinally of the screw for disengagement from the pinion, and means rotatable upon the screw for moving the gear longitudinally of the screw to disengage the gear from the pinion.

8. A housing screw provided with a head fixed thereon to rotate therewith, a gear connected with the head to rotate therewith and movable longitudinally of the screw for disengagement from a driving element, said gear projecting peripherally beyond the head, an annular member embracing the head and movable longitudinally of the screw to move the gear longitudinally of the screw, and a cam device mounted to rotate upon the screw in co-operative relation with the annular member to move the latter longitudinally of the screw.

9. A housing screw provided with a head fixed thereon to rotate therewith and provided with a plurality of projections extending in the direction of the screw, a gear having openings receiving the projections and movable on the projections longitudinally of the screw, said gear projecting peripherally beyond the head, an annular member embracing the head and movable longitudinally upon the screw for moving the gear longitudinally of the screw, and a cam device rotatably mounted upon the screw and associated with the annular member to move the latter longitudinally of the screw.

In testimony whereof, we have hereunto set our hands.

PAUL R. JOINSON.
FRED W. LODDING.
